W.M. Anderson, Inventor

By *Chasnow & Co.*
Attorney

UNITED STATES PATENT OFFICE.

WILLIAM M. ANDERSON, OF BOYCEVILLE, WISCONSIN.

COW-TAIL HOLDER.

Application filed July 22, 1922. Serial No. 576,900.

To all whom it may concern:

Be it known that I, WILLIAM M. ANDERSON, a citizen of the United States, residing at Boyceville, in the county of Dunn and State of Wisconsin, have invented a new and useful Cow-Tail Holder, of which the following is a specification.

This invention relates to cow tail holders, and the object thereof is to provide a simple, cheaply constructed and efficient device of this character which may be readily applied and removed, and which will automatically be detached should the cow become unruly.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:—

Figure 1 represents a perspective view of the device shown applied, and

Fig. 2 is a similar view on an enlarged scale of the device shown detached.

In the embodiment illustrated, the holder constituting this invention is preferably constructed of spring wire bent intermediate its ends to form a leg encircling open loop 1 which is designed to be passed around the leg of the milker, and which has connected therewith a tail clamp 5. This clamp 5 is constructed of two jaws 2 and 4, the former of which extends laterally from one end of the loop 1 and is bent at 3 to form a hand grip, and extended therefrom parallel with jaw 2 to form the movable or clamping jaw 4. This jaw 4 has its terminal deflected as shown clearly in Fig. 2 to form between it and the fixed jaw a V-shaped tail receiving space which facilitates the insertion of the tail.

The other end 6 of the open loop 1 is extended in a plane tangential to said loop and is provided with a plurality of longitudinally spaced hooks or fingers 7 formed by bends in said end 6. These hooks 7 are designed to be interlockingly connected with the loop 1 at the junction of the arm 2 therewith as is shown clearly in Fig. 2. A plurality of the hooks 7 are provided to adapt the loop 1 to fit legs of different sizes. The terminal of this end 6 is bent to form

a hook 8 which is also designed to be engaged in the same manner that the hooks 7 are to form a loop of the largest size.

The jaws 2 and 4 are connected by a clamping band 9 which encircles both of said jaws and is slidably mounted thereon to vary their gripping engagement with the tail which is inserted between them.

In the use of this device, the loop 1 is passed around the leg of the milker as shown in Fig. 1, and the clamp 5 has its open end arranged toward the milker and between the jaws 2 and 4 of which the cow's tail is inserted and held. The positioning of the device in the manner above set forth with the loop 1 clamped tightly around the leg of the milker will locate the clamp 5 so that when the cow switches her tail it will automatically pass between the jaws 75 of the clamp and be held. Should the cow become unruly and move relatively to the milker, the latch arm 6 will spring away from its connection with loop 1 and release the milker.

To release the tail, a little yank or pull is given to the tail moving it out from between the jaws 4 and 2.

The wire from which this device is constructed is preferably more or less flexible so that the connecting portion of the jaw 2 will be pliant and vibrate when a cow switches her tail so that she will not be made uncomfortable and yet will prevent the tail from switching in the milker's face.

It is of course to be understood that this holder need not necessarily be applied as shown in Fig. 1, but the loop 1 may be turned more or less laterally relatively to the milker's leg so that the tail if desired may be held further away such as is often necessary when wet.

I claim:—

1. A cow tail holder comprising a single piece of spring wire bent intermediate its ends to form a leg encircling open loop with a latch member at one end of said loop and with its other end extended laterally substantially at right angles to said loop and adapted to be engaged by said latch, said lateral end being extended and bent to form a hand grip with the terminal arranged to form a cooperating clamping jaw, and a slide connecting said jaws to vary their clamping engagement.

2. A holder of the class described comprising a single piece of wire bent intermediate

its ends to form a leg encircling loop, with one end thereof extended tangentially relative to the loop and provided with a plurality of longitudinally spaced hooks, the 5 other end of said wire being extended laterally from said loop and bent to form clamping jaws.

In testimony that I claim the foregoing as my own, I have hereto affixed my signature in the presence of two witnesses.

WILLIAM M. ANDERSON.
